ERECTOR MECHANISM

Theodore W. Kenyon, R.F.D. 2, Old Lyme, Conn.
Filed Feb. 15, 1961, Ser. No. 89,545
16 Claims. (Cl. 74—5.43)

This invention relates to an erection device for a vertical gyroscope and more particularly to an erection system which is achieved uniquely by utilizing reaction forces of jets of liquid emanating from ports into liquid of the same composition surrounding the entire gyro gimbaling system.

Objects and features of this invention are the provision of a novel erection system for a gyroscope utilizing reaction forces of jets of liquid emanating from ports into liquid of the same composition surrounding the entire gyro gimbaling system which is covered by a closing container.

Other objects and features of this invention are the provision of novel means for directing jet fluid to said outlets or ports, novel valve means for controlling the discharge of jet fluid from selected of said outlets, novel gravitationally controlled sensor means for controlling operation of said valve means, novel negative feedback means for opposing movement of the gravitationally controlled sensor means and balancer weight means together with means for altering relative positions of said balancing weight means and also the provision of pumping means within the container for directing jet fluid from the container for use as the erector jet fluid.

Additional objects and features of the invention are the provision of novel jet fluid operated erector means for gyroscopes and novel controls for the jet fluid erector streams emanating from jet fluid ports positioned to provide erector action by reaction forces of jet fluid emanating from the ports into confined liquid of the same composition surrounding the entire gyro gimbaling system.

Yet other objects and features of the invention are the provision of a novel method of effecting gyro erecting action of a gyroscope.

Still other objects and features of the invention are the provision of effective and relatively simple structural components for effecting the aforescribed erecting action.

Further objects and features of the invention are the provision of a readily assembled arrangement that is trouble free in operation and fully effective in producing erecting action with minimal input power and minimal fluid volume in the erector system.

Other objects and features of the invention will become apparent from the following specification and the accompanying drawings forming a part hereof wherein:

FIGURE 1 is a schematic section of an erection system embodying the invention with parts shown in one control position;

FIGURE 2 is a similar schematic view with the parts in a second control position;

Schematic system (FIGURES 1-3)

55 Referring now to the drawings and first to FIGURES 1, 2 and 3, the reference character 10 denotes an enclosing casing filled entirely with a high specific gravity, preferably transparent, liquid 11 for example Dow-Corning Silicone #200 which is non-corrosive and non-conductive.

60 Any other similar liquid may be used.

The casing 10 also includes a gyroscope G which includes a jet type erector system 12 for each of two mutually perpendicular X—X and Y—Y gimbal axes, only one of said systems 12 for the X—X gimbal axis being shown because the one for the Y—Y axis is identical. Also mounted within the casing 10 and completely submerged in the liquid 11 are a motor 13, and a pump 14 driven by the motor 13. A filter 15 is connected to the pump intake line 16 so that liquid drawn in at the intake

65 70 17 of the filter 15 must necessarily pass through the latter prior to its transit through the pump and ejection at the delivery conduit 18 of the pump.

Operation of the pump 14 by its motor 13 forces fluid under pressure to the input passageway 19 of the erector system 12. This passageway 19 opens into the wall of a cylindrical bore 20 in the housing 21 of the erector system 12. A tubular valve seat 22 is mounted in the bore 20 and is maintained in a fixed position therein as by a force fit. The longitudinal axis $b-b$ of valve seat 22 is aligned in parallelism with the Y-Y gimbal axis of gyro G as will be described. End plugs or caps 23 and 23a close off opposite ends of said bore 20. A port 24 in the valve seat 22 registers with the inner terminal of the input passageway 19 and is preferably centrally located relative to the length of the bore of said valve seat 22. Equispaced ports 25 and 26 at opposite sides of the port 24 register respectively with erection jet passages 27 and 28 whose outlet openings 27a and 28a open in opposite directions along the Y-Y axis in the upper portions 21a and 21b of the housing 21. Additional annular liquid power input ports 29 and 30 are provided adjacent opposite ends of the valve seat 22. These ports 29 and 30 communicate through inlet passageways 29a and 30a in housing 21 respectively with the separate conduits 31 and 32. The terminals 31a and 32a of these conduits 31 and 32 are connected at opposite faces of a block receiver 33 which is fixedly mounted in any suitable way. These terminals communicate respectively with passageways 34 and 34a in the block receiver 33. The passageways 34 and 34a terminate at open mouths 34b and 34c in the upper face of the block receiver 33 being separated by a partition 34d a distance of approximately a few hundredths of an inch, for example .032".

A cylindrical tubular piston power valve 35 having oppositely located head portions 36 and 37 is mounted slidably within the tubular valve seat 22. This power valve 35 is shorter in length than valve seat 22 so that it may slide along axis $b-b$ reciprocally to and fro between the end caps 23 and 23a that close the ends of bore 20 and valve seat 22. The ends of head portions 36 and 37 are provided with stop members 36a and 37a. A partition 36b divides the tubular bore of valve 35 into two separate chambers opening respectively towards the opposite ends of tubular valve seat 22.

A stem part 35a of the valve 35 lying between the pair of head portions 36 and 37 is of smaller diameter than the interior of the valve seat 22 and with the inner surface of the latter defines an annular chamber 38. This chamber 38 is in direct communication at all times with the input port 24 in valve seat 22 and input passageway 19 so that chamber 38 is always filled with liquid under pressure which is delivered to said passageway 19 by the pump 14.

The head portions 36 and 37 normally when valve 35 is centralized almost close off the respective ports 25 and 26. Since the power valve 35 is shorter than the length of valve seat 22, it with its partition 36b thus provides oppositely located chambers 39 and 40 between the partition 36b and plug 23 and partition 36b and end plug 23a. These chambers 39 and 40 communicate directly with the respective annular ports 29 and 30 in valve seat 22. The inlet passageways 29a and 30a in the housing 21 also are in direct communication with the ports 29 and 30 and thus permit valve operating fluid to enter or bleed from the chambers 39 and 40 as required to effect reciprocal shift of the valve 35 as will hereinafter be described. The open mouths 34b and 34c in the upper face of block receiver 33 serve as valve operating fluid power intake ports for the valve operating fluid which is delivered to them as will be presently described.

An outlet port 41 is provided in the valve seat 22 lying substantially diametrically opposite the intake port 24. Outlet port 41 communicates with a passageway 42 in housing 21 which is extended laterally of the axial direction of valve seat 22 and downwardly toward the two intake holes or openings 34b and 34c in block receiver 33, said passageway terminating in a fixed venturi-like jet nozzle

43 whose outlet 43a lies a substantial distance above the opening mouths 34b and 34c. The said power delivery jet outlet 43a of the fixed jet nozzle 43 projects into the inlet or mouth of a movable venturi-like jet 44 whose outlet orifice 44a is normally maintained substantially centrally located above the upper face of the partition 34d between the two open inlet mouths 34b and 34c in the upper face of block receiver 33. The two jets 43 and 44 are surrounded by a tubular random flow shield 45 which projects upwardly from the upper face of block receiver 33 and concentrically about the two jets 43 and 44. This shield 45 has a larger internal diameter than the peripheral or outer diameters of the jets 43 and 44 and at its upper open end terminates well above the level of the outlet 43a of the fixed jet nozzle 43.

The movable jet 44 is carried by a sensor rod or arm 46 which is pivotally supported to swing about a normally vertical sensor axis a that intersects the longitudinal normally horizontal axis of the fixed jet 43, and is also perpendicular to the longitudinal axis $b-b$ of the piston power valve 35 for purposes of elimination of coercion on the gyro gimbal. The sensor rod or arm 46 projects laterally outwardly of appropriate slots 47 in the random flow shield 45. These slots 47 are dimensioned to permit pivotal motion of the sensor rod or arm 46 about its pivot axis a . The sensor rod or bar 46 has a pendulum weight 48 at one side of the pivot axis a which projects into a fixed, tubular, random flow shield 49 between a pair of oppositely located, spaced apart adjustable sensor travel or limit stops 50 and 51. These stops 50 and 51 are carried by the fixed random flow shield 49. They are threaded so as to be individually adjustable to provide selectable limit stops for clockwise or counterclockwise gravitational swing of sensor rod or arm 46 and sensor weight 48 about pivot axis a . In the aforescribed normal disposition of the jet orifice 44a centrally over the partition 34d between open mouths 34b and 34c of block receiver 33, the weight 48 of said sensor rod 46 lies substantially centrally disposed between the two adjustable stops 50 and 51 as seen in FIGURE 1.

The jet 44 and its orifice 44a are tiltable about the pivot axis a in either a clockwise or counterclockwise direction to direct orifice 44a from its aforementioned normally centralized position between the mouths 34b and 34c toward a position overlying either of these mouths 45 depending upon the direction of gravitational tilt of sensor arm 46 about vertical axis a so that the jet discharge emitted by nozzle orifice 44a will be directed into the particular mouth or inlet orifice 34b or 34c toward which it is directed when a tilt in one direction or the other of jet nozzle 44 is effected. The extent and direction of tilt will of course determine the relative disposition of the jet orifice 44a with respect to the mouth or inlet orifice 34b or 34c toward which it has been tilted and thus serve as a regulatory arrangement for the quantitative amount and velocity of jet fluid that will actually enter the particular mouth or inlet orifice 34b or 34c as the case may be.

In order to effect negative fluid feedback counter to the gravitational tilt of the sensor arm 46 and jet nozzle 44, a feedback reaction plate 52 comprising oppositely directed vanes or blades 52a and 52b is secured to said rod or bar 46 at nozzle 44. These vanes or blades 52a and 52b respectively overlie the outlet ports of auxiliary fixed feedback jets 53 and 54. Needle valves 55 and 56 of conventional adjustable type provide a control for feedback jet fluid stream delivery from the outlet ports of said jets 53 and 54. The said jet ports respectively are directed toward the underfaces of the respective blades 52a and 52b being spaced from the latter so as not to physically impede tilting swing of jet nozzle 44 about sensor tilt axis a under action of gravity within the limits permitted by the respective sensor travel limit stops 50 and 51. Feedback jet fluid delivered via the output port of fixed reaction jet nozzle

53 will tend to effect clockwise tilt of sensor arm 46 counter to counterclockwise gravitational tilt thereof by impingement against vane or blade 52a thus tending to swing jet nozzle orifice 44a toward its central position with respect to mouths or inlet orifices 34b and 34c. This condition is illustrated in FIGURE 2. On the other hand impingement of feedback jet fluid delivered via the outlet port of fixed reaction jet nozzle 54 against vane or blade 52b will tend to effect counterclockwise tilt of sensor arm 46 counter to clockwise gravitational tilt thereof by impingement against vane or blade 52b thus tending to swing jet orifice 44a toward central position with respect to mouths or inlet orifices 34b and 34c. These feedback jets 53 and 54 serve purposes presently to be described.

Condits 57 and 58 connect the respective fixed reaction or feedback jets 53 and 54 to the respective ports 59 and 60 which are provided in the tubular valve seat 22. These ports 59 and 60 are equispaced and lie on opposite sides of the main outlet port 41 in said tubular valve seat 22. Capillary conduits 61 and 62 are connected respectively at one of their ends to communicate with the respective conduits 57 and 58. The other ends of the respective conduits 61 and 62 are connected to communicate with opposite ends of a balancing cylinder 63 which contains a slideable balance weight 64. A position indication rod 65 attached to one end of the weight 64 is movable in the preferably transparent closed sighting sleeve 66 provided at one end of cylinder 63. This sleeve 66 provides a viewing port for the rod 65 to enable visual determination of the position of the balance weight 64 in the balance cylinder 63. It is used primarily during initial calibration of the entire system. The longitudinal axis c—c of balance weight 64 and its cylinder 63 lies parallel with or aligned with the axis b—b of the power valve 35.

The system just described is located in parallelism with for example the Y—Y gimbal axis of the gyro G. In other words, the axes b—b and c—c are parallel with the Y—Y gimbal axis of the gyro.

A second identical system (not shown) is located at 90° with the system described so that its power piston axes and balance cylinder axis are parallel with the X—X gimbal axis of the gyro. It is necessary to have these two cross arranged identical systems to effect complete gyro erection on both the X—X and Y—Y axes.

Operation of schematic system

It is to be noted that the outlet ports 25, 26, 59 and 60 of the valve seat 22 in the normal centrally located position of the power valve 35 are almost closed off from communication with the fluid input chamber 38. There is, however, a small overlap of chamber 38 with respect to all four of the said outlet ports in this normal central position of said valve so that some bleed occurs of hydraulic input power supplied to chamber 38 by operation of pump 14 through the hydraulic power input passageway 19 and port 24. The said normal centrally located position of main power valve 35 is that intended to occur when gimbal axis X—X of the gyro is horizontal. The slight bleeds from chamber 38 of the hydraulic fluid fed thereto via ports 25 and 26 are of like magnitude and at this time provide equal and oppositely directed discharges of bleed erector jet fluid via the oppositely directed erector jet openings 27a and 28a into the body of fluid 11 within the casing 10. The opposite equal reactions produced in the fluid body 11 of these bleed jets cancel each other out. The slight bleeds at this time also from chamber 38 via ports 59 and 60 pass out through feedback conduits 57 and 58 to the feedback reaction jets 53 and 54 and impinge against the respective feedback reaction plate vanes 52a and 52b. The respective needle valves 55 and 56 are adjusted so that the bleed flow from the respective reaction jets that impinge against the vanes 52a and 52b

balances the reaction plate 52 and sensor arm on the vertical pivot axis a so that the weight 48 of sensor arm 46 then lies midway between the two limit stops 50 and 51. The capillary conduits 61 and 62 also deliver 5 bleed fluid from the respective feedback conduits 57 and 58 to opposite sides of balance weight 64 in balancing chamber 63.

At this time hydraulic fluid from chamber 38 also passes outwardly of the latter via port 41 and to power jet nozzle 43a and from the latter to power jet nozzle outlet 44a against the outer surface of partition 34d of the block receiver 33 over which it then lies. The emerging jet stream at 44a striking the surface of this partition 34d is divided and enters both opening 34b and 15 34c equally, thus producing no effect on the piston. This balanced arrangement persists as long as no tilt or displacement of the gyro assembly occurs about the Y—Y axis.

Assume now that the surface F—F' of the gyro assembly 20 is inclined about the Y—Y axis with rotor wheel G rotating clockwise so that F' lies below and F lies above horizontal. This is the condition shown in FIGURE 2. Gravity causes the sensor arm 46 to tilt counterclockwise (FIGURE 2) about vertical axis a and likewise tilts movable sensor operated jet 44 counterclockwise causing its 25 outlet orifice 44a to be directed toward sensor orifice 34c directing the emerging power jet stream from jet orifice 44a into said sensor orifice 34c whence it is forced via passageway 34a in block receiver 33 and conduit 32 30 and port 30 into the right chamber 40 of the power valve 35. This increases fluid pressure in said chamber 40 relative to that in chamber 39 effecting a leftward displacement of power valve 35 as seen in FIGURE 2. This forces fluid from chamber 39 to bleed outwardly 35 thereof via port 29, conduit 31 and opening 34b.

The leftward displacement of valve 35 causes head 37 of the power valve to close off ports 26 and 60 completely while head 36 having also been displaced leftwardly further uncovers both ports 25 and 59. A large volume of 40 pumped jet fluid flow from chamber 38 via port 25 and passage 27 to erector jet outlet 27a now occurs. Since erector jet flow from erector jet outlet 28a has at this time been cut off by closing of the port 26, the erector jet stream emerging at outlet 27a into the main body of 45 fluid 11 provides a reactor erector correcting torque force which tends to restore the gyro assembly to its initial level condition shown in FIGURE 1, i.e. with surface F—F' horizontal.

At the same time since port 59 has been more widely 50 opened and port 60 has been closed only jet fluid from sensor signal reaction jet 53 can flow while that from sensor signal reaction jet 54 has been cut off. This feedback jet flow tends to swing sensor arm 46 clockwise 55 negatively of the gravitational tilt tendency towards its other limit stop 50. This negative swing influence tends to direct the jet from orifice 44a into opening 34b and hence to refill chamber 39 tending thus to restore cylinder 35 to its initial balanced condition shown in FIGURE 1. This swing of sensor arm 46 occurs during existence 60 of the erector jet stream issuing at erector jet orifice 27a. When restoration of surface F—F' to level condition is complete the balanced condition of FIGURE 1 recurs at which time the power jet stream issuing from the now centrally restored position of jet orifice 44a relative to 65 openings 34b and 34c will not effect further movement of power piston 35.

The same type of erector action occurs with emission 70 of an erecting jet stream from erector jet nozzle 28a rather than erector jet nozzle 27a if the initial unbalance is one wherein F' is higher and F is lower than a horizontal position. The balance weight 64 under influence 75 of opposing pressures in capillary lines 61 and 62 tends at all times to try to effect balance in the system and maintenance in its non-tilted condition of FIG. 1.

The other like system (not shown) provides like erecting action with respect to tilts about the Y—Y axis.

With either of these two erector systems, the power valve 35 has its position controlled by the sensor weight 48 and sensor arm 46. Power valve 35 thus valves jet fluid to the correct erector jet outlet, e.g. 27a or 27b as the case may be, to produce torque by reaction with the main body of the same fluid in the casing and thereby produce gyro precession in a direction to correct the vertical error that caused the sensor weight and sensor arm motions. The system shown in FIGURES 1 and 2 provides for erecting action on one X—X axis of the gyro, and a similar system is provided to provide jet torque components operating in the gyro X—X axis to provide erection in the Y—Y axis displaced 90° from the described X—X axis.

An advantage of the device is that a very accurate erection system can be obtained with a small set of components and with very low power input to the erection system. For example, in the practical embodiment to be described, erection is normally achieved with approximately one watt of input power in one cubic inch of erector equipment in the erector system.

In addition, an automatic self balancing or integrating erection system is readily obtained to provide an even greater accuracy with a gyro that need not itself be accurately balanced.

Practical embodiment

A practical embodiment of the invention as just noted is depicted in FIGS. 3 et seq. Referring to these figures, the reference character 110 denotes an enclosing casing which is filled with high specific gravity liquid 111 of the same type as liquid 11 hereinbefore described. A gyroscope Ga is mounted in this casing as will be described. The jet type erector system 112 is carried by the gyro Ga being supported, for example, on the upper surface S of the gyro-rotor housing Gh. An electric motor 113 is secured to the base 110a of casing 110 and a gear type pump 114, also secured to base 110a is adapted to be driven by the motor 113. A filter 115 also secured to base 110a is connected to the pump intake line 116 so that liquid 111 within casing 110 that is drawn in at the intake 117 of the filter 115 when the motor 113 is driven must necessarily pass through the filter 115 prior to its entry into and passage through the pump 114.

The outlet 118 of the pump 114 overlies an inlet 119 of a distributing passageway 120 (FIGS. 3, 4 and 5), which is provided in the base 110a. Branch passageways 120a and 120b each communicating with the distributing passageway 120 are provided in said base 110a and these passageways in turn have outlets 120c and 120d (FIGS. 3, 4 and 5) which communicate respectively with vertical passageways 121 and 121a provided in the respective oppositely located vertical gyro support posts 122 and 122a which are secured to the base 110a. The pump 114 thus serves to supply fluid pumped from the fluid 111 in casing 110 under pressure to both the vertical passageways 121 and 121a in respective gyro supports 122 and 122a and this fluid under pump created pressure is utilized to provide the jet erection torques as will be presently described.

The spaced-apart vertical gyro support posts 122 and 122a have axially aligned openings 123, 123a (FIG. 5) in which ported ball bearing supports 124, 124a (FIGS. 5 and 12) are mounted. These ball bearing supports 124 and 124a are generally ring shaped, being provided with an annular surface groove 125, 125a between a pair of spaced inner and outer annular flanges 126, 126a, 127, 127a. The inner flanges 126, 126a of each support fit within one of the respective openings 123 and 123a. The annular grooves 125 and 125a respectively communicate with the upper open ends of passageway 121 or 121a in the respective supports 122, 122a. The inner faces of outer flanges 127, 127a abut the outer face of respective

support posts 122 and 122a to maintain the bearing supports 124 and 124a in place.

A plurality of ports 18 or 128a in the annular walls of grooves 125 and 125a provide fluid passage communications from the respective open upper ends of passageways 121 and 121a into the outward spaces 129 and 129a externally of the bearing supports 124 and 124a. These outward spaces 129 and 129a are closed off by the respective cover plates 130 and 130a which are secured as by bolts 130c and 130d to respective support posts 122 and 122a and are insulated from these posts and with respect to flanges 127 or 127c by pairs of packing and insulation rings 131 and 131a. Electrical contact springs 132 and 132a are carried insulatively between the ring pairs 131 and 131a located between these end plates 130 and 130a for purposes presently to be described.

Ball bearings 133 and 133a are mounted respectively, within the tubular supports 124 and 124a and there serve as mounts for the diametrically disposed tubular trunnions 134 or 134a of the outer gimbal 135 of gyro Ga (FIGS. 5 and 11). The trunnions 134 and 134a are provided with the respective chambers 136 and 136a which communicate respectively with the center bores 137 and 137a of the respective trunnions 134 and 134a. These chambers 136 and 136a respectively communicate via openings 136b and 136c (FIG. 11) with open ends of respective passageways 138 and 138a in the gimbal frame 135. The other ends of passageways 138 and 138a open respectively into the diametrically opposite bearing openings 139 and 139a in the said outer gimbal frame 135 (see FIGS. 4 and 11).

Tubular ball bearing supports 140 and 140a (FIG. 4) of substantially identical construction with the bearing supports 124 and 124a are positioned in the bearing openings 139 and 139a of outer gimbal 135. The outer ends of the central openings in the supports 140 and 140a are closed off by cover plates 141 and 141a (FIG. 4) which are insulatively separated from the outer flanges 142 and 142a of said supports 140 and 140a by pairs of packing and insulating rings 143 and 143a, defining the respective chambers 144 and 144a which communicate respectively with the annular grooves 145 and 145a of the bearing supports 140 and 140a via ports 146 and 146a. The said annular grooves 145 and 145a respectively communicate with the second open ends of passageways 138 and 138a of the gimbal 135 (FIG. 11). Contact springs 147 and 147a (FIG. 4) are insulatively carried between the pairs of insulator rings 143 and 143a and project into the respective spaces 144 and 144a for purposes presently to be described.

Ball bearings 148 and 148a are mounted within the tubular bearing supports 140 and 140a and these serve as mounts for the diametrically disposed hollow or tubular trunnions 149 and 149a of the inner gimbal or rotor frame Gh. This frame Gh is provided with the respective chambers 150, 150a which communicate respectively with the bores 151, 151a of the respective hollow trunnions 149 and 149a. These chambers 150 and 150a in turn communicate with respective passageways 152, 152a provided in the cover 153 of the rotor frame Gh and the open delivery terminals of these passageways are disposed in the upper surface of cover 153.

The inner gimbal or rotor frame Gh encloses an electrically driven gyro rotor wheel 155 supported by ball bearings 156, 157 to spin about its normally vertical shaft 158 which extends transversely between the cover 153 and bottom 159 of the rotor covering frame Gh. The rotor wheel 155 is provided with a conventional rotor 160 which cooperates inductively with stator windings 161 supported concentrically about the shaft 158 within a space 162 provided in the rotor wheel 155 so that appropriate electric energization of the stator windings 161 and rotor 160 will cause the rotor wheel 155 to spin preferably clockwise about shaft 158.

With the arrangement thus far described, the outer gimbal ring is supported by its trunnions 134 and 134a to be freely rotatable about the Y—Y roll axis of the device on which the gyro is mounted while the inner gimbal or rotor housing or rotor frame Gh supported by its trunnions 151, 151a to be freely rotatable about the pitch or X—X of said device, which is displaced 90° from the roll axis.

The liquid 111 within casing 110 which pumped by pump 114 to the distributing passageways 120, 120a and 120b is, via the various passageways and ports hereinabove described able to reach the outlets 152 and 152a in the cover 153 of the rotor housing or frame Gh in any and all pitch or roll positions of the outer gimbal frame 135 and of the inner gimbal or rotor housing frame Gh.

Erector system

The jet erector system 112 is carried on the top surface S of the cover 153 of the inner gimbal or rotor frame Gh being preferably centered relative to the shaft 158.

This jet erector system 112 includes an erector body base plate 163 (FIGS. 4, 5, 18 and 19) secured as by bolts 164 passing through holes 165 to the upper face of rotor frame cover plate 153. This base plate 163 is undercut at 166 (FIG. 18) to define an annular rim 167 which rests firmly on the surface of cover plate 153. The undercut 166 is primarily to better leak-proof contact between the rim 167 and surface of the cover plate 153 allowing for non-flatness of said cover plate. A central hole 168 is provided in the base plate 163. Oppositely extending channels 169 and 170 and a third channel 171 perpendicular to the channels 169 and 170 are provided in the base plate 163. The channels 169, 170 and 171 extend radially outwardly from the center hole 168 terminating short of the outer periphery of base plate 163. Their inner ends communicate with hole 168. Passage holes 172 and 173 in the base plate 163 are located near the outer ends of channels 170 and 171 and open into the upper outer surface of base plate 163 (FIGS. 4, 5 and 18).

Erector body block

An erector body block 174 of generally cubical configuration is secured to the erector base plate 163 as by the bolts 175 (FIGS. 3, 4, 5, 6-10 and 13-16 inclusive) so that its opposite pairs of side faces A, B and C, D, are respectively perpendicular to the Y—Y and X—X axes. The bottom face of the erector body block 174 is provided with a centrally located cylindrical recess 176. This recess 176 is positioned to overlie the hole or opening 168 in the erector base plate 163 (FIG. 8) being approximately of the same diameter as the latter.

A transverse, horizontally disposed power piston bore or hole 177 extending through the block 174 from the face A to the face B thereof is provided, this bore being parallel with the X—X gimbal axis. A centrally located vertical hole 178 in block 174 provides communication between recess 176 and said bore 177. (See FIGURES 16 and 17.) Small diametered balancer passageways 179_L and 179_R extending respectively from near opposite ends of bore 177 outwardly to the face D of body block 174 are provided. Other small diametered reaction jet passageways 180_L and 180_R extending respectively from near opposite ends of bore 177 outwardly to face C of body block 174 are provided.

A second transverse horizontally disposed power piston bore or hole 181 extending through the block 174 through from the face C to the face D thereof and perpendicular to bore 177 is provided, this bore being parallel with the Y—Y gimbal axis. A centrally located vertical hole 182 joints bores 177 and 181.

Balancer openings or passageways 183_L and 183_R near opposite ends of the bore 181 extend laterally from said

bore 181 to the face B of said block (FIGS. 13 and 15). Other small diametered reaction jet passageways 184_L and 184_R extending respectively from near opposite ends of bore 181 outwardly to face A of body block 174 are provided (FIGS. 13, 15 and 16).

A pair of spaced-apart erection jet flow vertical holes or passageways 185 and 186 (FIGS. 3, 4, 5, 8, 9 and 13-17 inclusive) extend upwardly from the bore 177 to the upper surface of a substantially cylindrical extension 187 of block 174 at its top. A similar pair of spaced-apart erection jet flow vertical holes or passageways 188 and 189 extend upwardly from bore 181 to the upper surface of said cylindrical extension 187. The four upper open ends of these holes or passageways 185, 186 and 188, 189 as seen clearly in FIG. 13 lie 90° apart and are concentrically disposed relative to the central vertical axis Z—Z of block 174, which axis is aligned with the axis of the rotor shaft 158. The cylindrical extension 187 has a threaded hole 190 aligned with its axis Z—Z.

20 A cylindrical block 191 (FIGS. 3, 4, 5, 8 and 9), the same diameter as block extension 187 is positioned to overlie the latter. This block 191 has four vertically extending passages or holes 192, 193, 194 and 195 of the same diameter as and registering respectively with the 25 holes or passageways 185, 186, 188 and 189 serving as continuations of the latter. The upper ends of holes or passageways 192, 193, 194 and 195 terminate in the upper surface of block 191. They are provided respectively with substantially rectangular independent, laterally directed 30 erector jet orifice channels or passageways 192a, 193a, 194a, and 195a which open respectively at 90° spaced apart points in the cylindrical surface of block 191. Jet orifices 192a and 193a are diametrically opposed and in line with the X—X axis of the gyro Ga while jet orifices 35 194a and 195a are diametrically opposed and in line with the Y—Y axis of the gyro Ga. A cover disk or plate 196 overlies the top surface of block 191 and its bottom face provides the covering walls for the independent erector jet orifices 192a, 193a, 194a and 195a. The cover plate 40 196 and the block 191 are secured to the cylindrical extension 187 as by a threaded center bolt 197 (FIGURE 3) which engages the threaded hole 190 (FIG. 16) in said extension 187.

The power cylinder bore 177 in erector body block 174 45 has a pair of spaced-apart, fluid power input and bleed passageways 198_L and 198_R (FIGS. 14 and 15) located near the opposite ends of said bore 177 and extending laterally therefrom to the outer face C of the block 174. The bore 181 also has a pair of spaced-apart fluid power 50 input and bleed passageways 199_L and 199_R (FIGS. 13-17 inclusive) located near opposite ends of said bore 181 and extending laterally therefrom to the outer face B of the block. The passageways 198_L and 198_R terminate in face C in substantially L-shaped recesses 200_L and 200_R 55 provided in said face C (FIG. 15).

The passageways 199_L and 199_R terminate in face B in substantially L-shaped recesses 201_L and 201_R provided in said face B (FIG. 14).

Power valve seats and power valves

A tubular valve seat insert or sleeve 202 (FIGS. 20 and 21) is provided for the bore 177. This valve seat 202 has a centrally disposed annular groove 203 in its outer surface which communicates with its center hole or bore 65 204 via a plurality of wall holes 205. When the valve seat insert 202 is fitted into bore 177, the annular groove 203 lies in direct communication with the passageways or holes 178 and 182 of erector body block 174 (see FIG. 9). The valve seat 202 also has a pair of annular grooves 70 206_L and 206_R in its outer surface which are equi-spaced from and lie at opposite sides of the annular groove 203. These grooves 206_L and 206_R communicate respectively with the center hole 204 via a plurality of wall holes 207_L and 207_R. When valve seat 202 is fitted into bore 177, 75 the annular grooves 206_L and 206_R respectively die in

direct communication with the respective erector jet passageways 185 and 186 (see FIG. 9) and also with respective reaction jet passageways 180_L and 180_R. Additional outer annular recesses 208_L and 208_R are provided at opposite ends of valve seat 202. Radial slots 209_L and 209_R spaced 90° apart are provided at the opposite ends of sleeve 202.

End stop rings 210_L and 210_R are fitted into the opposite ends of sleeve valve seat 202. Diametrically disposed radial slots 211_L and 211_R are provided in these end rings, the said rings being positioned so that their radial slots 211_L and 211_R lie aligned with a pair of the radial slots 209_L and 209_R so as to provide direct communication between the recesses 208_L and 208_R with opposite ends of the valve seat hole 204. The composite length of sleeve valve seat 202 and its end rings 210_L and 210_R is equal substantially to the length of bore 177 between faces A and B.

A power valve 212 (FIG. 23) is fitted slidably within the tubular valve seat insert 202. This valve is a tubular cylindrical body having oppositely located head portions 213_L and 213_R. These head portions have approximately the same external diameter as the inner diameter of the valve seat bore 204 but fit slidably within the latter. A stem part 214 lying between the head portions 213_L and 213_R is of smaller diameter than the diameter of bore 204 of valve seat 202 and with the surface of said bore defines an annular chamber 215. This chamber 215 is at all times in communication with the input ports 205 in valve seat 202 and also input passageways 178 and 182 (FIGS. 3, 16 and 17), so that chamber 215 is always filled with liquid under pressure which is delivered to said passageway 178 by the pump 114 (FIG. 3) via passageways 120, 120_a, 120_b and 121, 121_a, chamber 125, 125_a (FIG. 5), ports 128, 128_a, chambers 137, 137_a, passageways 138, 138_a in gimbal ring 135 (FIG. 11) channels 145, 145_a, ports 146, 146_a, chambers 144, 144_a, bores 151, 151_a and passageways 152, 152_a whose outlets open into the recesses 169 and 170 which communicate with hole 168 and then with recess 176 in the erector body block 174. The power valve 212 is shorter in length than the tubular valve seat insert 202 so that it may slide reciprocally to and fro between opposite ends of the valve seat bore 204. A transverse partition 216 divides the tubular bore of power valve 212 into two separate chambers 217_R and 217_L opening respectively toward opposite ends of the valve seat bore 204.

The head portions 213_R and 213_L of the power valve 212 normally when the latter is in a centralized position in bore 204 nearly close off the respective port holes 207_L and 207_R leaving, however, minimal bleed openings 218_R and 218_L (FIG. 23) into port holes 207_L and 207_R for purposes presently to be described.

A power valve seat insert or sleeve 202_a which is identical with power valve sleeve 202 is provided for the second valve bore 181 (FIG. 4) in the erector body block 174 (FIG. 4). This valve sleeve 202_a receives an axially slidible power piston 212_a identical in construction with power piston 212. The components of the sleeve 202_a and of piston 212_a which correspond to those of sleeve 202 and piston 212 bear the same reference characters with the added subscript *a*.

The opposite ends of valve bores 177 and 181 of the erector body block 174 which terminate in the faces A, B, C and D thereof are closed off. The closing off arrangements are best seen in FIGS. 3 to 9 inclusive, 13, 28 and 29. Thus, the end of bore 181 which terminates in face D (FIGS. 5, 8 and 13) of erector body block 174 is closed off by a cover plate 219 secured to the said erector body block 174 as by bolts 220. The end of bore 177 which terminates in face B of said erector body block 174 is closed off by a similar cover plate 221 (FIGS. 6 and 13) secured to said block 174 as by bolts 222.

The opposite end of bore 177 in erector body block

174 which terminates in its face A is closed off by a plate separator 223 (FIG. 28) while the opposite end of bore 181 which terminates in face C of said erector body block 174 is closed off by a plate separator 224 (FIG. 29). The two plate separators 223 and 224 respectively have areas and shapes corresponding to the areas and shapes of the respective faces A and C of said body block 174.

Plate separator 223 has a pair of spaced-apart holes 225_L and 225_R positioned to lie aligned with the respective outlets of feedback balancer passages 180_L and 180_R (FIGS. 5 and 28). It also has a pair of spaced-apart holes 226_L and 226_R that lie aligned with portions of the respective L-shaped fluid power supply passageways 200_L and 200_R (FIGS. 5, 15 and 28). Bolt holes 227 are also provided in the plate separator 223.

Plate separator 224 (FIG. 29) has a pair of spaced-apart holes 228_L and 228_R positioned to lie aligned with the respective outlets of feed back balancer passages 183_L and 183_R (FIGS. 4 and 29). It also has a pair of spaced-apart holes 230_L and 230_R that are aligned with portions of the respective L-shaped fluid power supply passageways 201_L and 201_R (FIGS. 4, 14 and 29). Bolt holes 231 also are provided in the plate receiver 224.

Block receivers (FIGS. 4, 5, 30, 31 and 32)

Block receivers 232 and 232_a of identical construction are mounted respectively on the outer faces of the respective plate separators 223 and 224. As they are identical only block receiver 232 is described, it being understood that corresponding components of block receiver 232_a are similarly designated with added subscripts *a*. The block receiver 232 is a substantially rectilinear body (FIGS. 4, 5, 30, 31 and 32). The face F_L thereof that rests on the plate separator 223 is provided with a pair of longitudinally extending channels or recesses 233_L and 233_R separated by a partition 234. These channels respectively are aligned with the holes 226_L and 226_R in the plate receiver 223 so that they communicate with the respective L-shaped slots 200_L and 200_R in the face C of erector body block 174. Transverse holes or passageways 235_L and 235_R extend from the respective channels 233_L and 233_R in block receiver 232 through the latter to its outer face F_u terminating there in open inlet holes 236_L and 236_R. These open inlet holes 236_L and 236_R lie in a common horizontal plane which is parallel with the X—X axis of the gyro Ga being spaced apart a small distance for example .032 inch between centers and each being approximately .0260" in diameter. The portion of the partition 234 between these holes 236_L and 236_R is approximately .006" thick. It is understood, of course, that these dimensions are by way of example only. No intention of limitation to these exact figures is intended. Bolt mounting holes 237 are provided in block receiver 232 which are intended to lie aligned with a corresponding pair of the bolt holes 227 in plate separator 223 so that the latter and the block receiver 232 may be mounted on the face C of erector body block 174 by common bolts 238 (FIG. 5).

The second block receiver 232_a is mounted on the face of plate separator 224 and with the latter to the face B of the erector body block 174 by common bolts 238_a (FIG. 4). The channels 233_{La} and 233_{Ra} of this block receiver lie aligned respectively with the holes 230_L and 230_R (FIGS. 4 and 26). Its two inlet holes 236_{La} and 236_{Ra} lie in a common horizontal plane which is parallel with the Y—Y axis of the gyro Ga.

Feed-back arrangements

70 A feedback block 239 (FIGS. 5 and 6) is also mounted on the outer face of plate separator 223 and with it to erector body block 174 as by bolts 240. This feedback block 239 lies above the block receiver 232. It includes a pair of separate horizontally disposed separate channels 241_L and 241_R which lie aligned respectively with

the feedback holes 225_L and 225_R in plate separator 223 thus being in communication with the respective feedback passages 180_L and 180_R in erector body block 174. Transverse passages or feedback holes 242_L and 242_R terminating in feedback jet outlets 243_L and 243_R in the outer face of feedback block 239 are provided in the latter. Needle valves 244_L and 244_R provide independent adjustable flow controls for feedback fluid flow outwardly of feedback jet outlets 243_L and 243_R. The two feedback jet orifices or outlets 243_L and 243_R lie spaced apart in a horizontal plane parallel with the surface S of the gyro rotor housing G. These two feedback jet orifices or outlets 243_L and 243_R are symmetrically disposed relative to the vertical center plane of the feedback block 239.

A similar feedback block 245 is also mounted on the outer face of plate separator 224 and with it to erector body block 174 as by bolts 246 (FIGS. 4 and 6). This feedback block lies above the block receiver 232_a. It includes a pair of separate angularly disposed separate channels 247_L and 247_R (FIGS. 4 and 6) which lie aligned with the respective feedback holes 228_L and 228_R of the plate separator 224 (FIG. 26) thus being in communication with the respective feedback passages 183_L and 183_R in erector body block 174. Transverse passages or feedback holes 248_L and 248_R terminating in jet outlets 249_L and 249_R in the outer face of feedback block 239 are provided in the latter. Needle valves 250_L and 250_R provide independent adaptable flow controls for feedback fluid flow outwardly of jet outlets 249_L and 249_R. The two feedback jet outlets or orifices 249_L and 249_R lie spaced apart in a horizontal plane parallel with surface S of the gyro rotor housing G. These jet outlets or orifices 249_L and 249_R are symmetrically disposed relative to the vertical center plane of the feedback block 245.

Sensor systems

A pair of sensor pivot supports 251_X and 251_Y are provided (FIGS. 3, 4 and 5). These supports are identical in construction and are mounted on the upper face of the rotor casing cover plate 163. Sensor pivot support 251_X (FIGS. 3, 5, 7, 10 and 25) is secured to plate 163 as by bolts 252_X. It has a vertical passageway 253_X that overlies the power fluid input outlet 172 in cover plate 163. A horizontal passageway 254_X communicates at its inner end with the vertical passageway 253_X and extends to the vertical surface 255_X of said support 251_X lying there at the same level as the level of the orifices 236_L and 236_R of the block receiver 232 with its axis centered between said two orifices. A fixed jet 256_X (FIGS. 5, 7, 10 and 25) is positioned rigidly in the outlet end of horizontal passageway 254_X and projects outwardly of the surface 255_X of said support 251_X toward the block receiver 232 with its axis centered relative to the partition 234 between the orifices 236_L and 236_R.

A pair of horizontally disposed, vertically spaced-apart pivot supporting flanges 257_X and 258_X (FIGS. 5 and 10) extend outwardly from face 255_X of said sensor pivot support. Flange 257_X abuts the top surface of cover plate 163 while flange 258_X lies aligned therewith in superposed relationship. A jewel bearing comprising a cap jewel 259_X and ring jewel 260_X carried by a tubular setting 261_X is fitted within a vertical jewel bearing receiving hole 262_X provided in flange 257_X. A vertical tapped hole 263_X is provided in the flange 258_X which lies vertically aligned with the lower hole 263_X. A threaded jewel bearing housing 264_X is threadably mounted in the tapped vertical hole 263_X being provided with a setting nut 265_X. This housing 264_X has a vertical recess 266_X. A jewel setting 267_X including a cap jewel 268_X and ring jewel 269_X is fitted into the recess 266_X of said adjustable housing 264_X.

A vertical sensor pivot shaft 270_X is supported between the vertically aligned fixed jewel bearing setting 261_X and adjustable jewel bearing setting 267_X as by the oppo-

sitely extending hardened steel pintles or pivots 271_X and 272_X which are fixedly mounted in opposite ends of the pivot shaft 270_X.

A horizontally tubular sensor jet 273_X is fixed in an appropriate horizontal opening 274_X in the pivot shaft 270_X. The axis of this jet 273_X lies aligned with the axis of fixed jet 256_X and the outlet orifice of the latter projects into the receiving end of sensor jet 273_X. The jet outlet 275_X lies horizontally aligned with the receiving orifices 236_L and 236_R in the block receiver 232 (FIG. 25) and is intended to be swingable reciprocally on a horizontal arc k_X (FIG. 7) from a central position relative to the partition 234 in clockwise and counterclockwise direction respectively toward and away from the two jet orifices 236_L and 236_R for purposes of directing jet fluid into the selected one of these two orifices as required by operating conditions presently to be described. The inner diameter of the bore of pivoted sensor jet 273_X at its receiving end is substantially larger than the outer diameter of fixed jet 256_X which projects into it so as to permit pivotal swing of jet 273_X relative to the jet orifices 236_L and 236_R of the block receiver 232 on the arc k_X.

A random flow shield 276_X (FIGS. 3, 6, 7 and 24) is secured to the sensor pivot support 251_X as by bolts 277_X. This random flow shield extends from support 251_X into contact with the block receiver 232 and surrounds the fixed jet 256 and movable jet 274 as well as orifices 236_L and 236_R in block receiver 232 to protect all from random flow currents of liquid 111 in casing 110.

30 A sensor arm or rod 278_X (FIGS. 6, 7 and 26) is clamped as at 279_X to the pivot shaft 270_X above the random flow shield 276_X. This rod 278_X extends horizontally from the pivot shaft 270_X at a 90° angle with respect to the common axis of the jets 273_X and 256_X.

35 A pendulum weight 280_X (FIG. 24) is secured to the under face of the free end of arm or rod 278_X as by bolts 281_X. This weight 280_X is substantially rectilinear in shape and its parallel side faces lie in spaced relationship between the vertical uprights 282_X, 283_X of a dash pot member 284_X which latter is secured as by bolts 285_X to the cover plate 163 of the rotor housing G. Adjustable limit stop screws 286_X and 287_X provide travel limits to the clockwise or counterclockwise swing of the pendulum weight 280_X and its sensor support arm 278_X on the vertical axis of the sensor support shaft 270_X. A random flow shield 288_X is secured to the vertical uprights 282_X and 283_X and projects therefrom toward the random flow shield 276_X (FIG. 7) serving to protect the pendulum weight 280_X from the effects of random flow currents of fluid 111 in the casing 110. The pivotal gravity swing of this pendulum weight 280_X on the vertical axis of vertical pivot rod 270_X is thus influenced by the dash pot effect of escapement of fluid outwardly through the open ends of the shield 288_X.

50 In normal position when the plane 55 of rotor cover 163 is horizontal, relative to the Y—Y axis, the pendulum weight 280_X lies centered between the two stop screws 286_X and 287_X as shown in FIG. 24 and may swing toward or away from either.

A jet reaction vane or plate 291_X (FIG. 6) is secured 60 suitably to the inner side face of sensor arm 278_X. This reaction vane or plate is substantially rectangular in shape and is admeasured lengthwise to be somewhat longer than the spacing between the reaction jet orifices 243_L and 243_R of the feedback block 239 lying parallel with the outer face of the latter and disposed symmetrically relative to the vertical axis of sensor support shaft 270_X so that reaction jets delivered by said jet orifices 243_L and 243_R and impinging on said vane or plate 291_X will have opposing swing effects on sensor arm 278_X about the axis 70 of said sensor support shaft 270_X.

The sensor pivot support 251_Y (FIG. 4) which is identical with sensor pivot support 251_X has associated with it a group of components of like kind as those associated with support 251_X and as just described, all being identified by like reference characters bearing subscripts y.

The reaction vane or plate 291_Y of this group of components is located to be influenced by the reaction jets emerging from the reaction jet orifices 249_L and 249_R (FIG. 6) of feedback block 245 to influence swing of the sensor arm or rod 278_Y between limits set by the adjustable screw stops 286_Y and 287_Y.

Balancer systems

Balancer cylinder blocks 292_X and 292_Y (FIGS. 4, 5, and 6) preferably of aluminum alloy are secured to the rotor housing cover 163 in any appropriate manner so that the axes of their cylinder bores 293_X, 293_Y are in crossed relationship being respectively parallel with the X—X and Y—Y axes of the gyro system. End wall plugs 294_X, 294_Y, preferably of aluminum alloy for each of the cylinder blocks 292_X, 292_Y close off one end of each cylinder bore 293_X, 293_Y. Headers 295_X, 295_Y close off the opposite ends of the respective bores 293_X, 293_Y, said headers being appropriately secured in place as by bolts (not shown) on the respective ends of said cylinder blocks 292_X, 292_Y. A tubular transparent viewing cap 296_X, 296_Y, for example, of "Plexiglas" or equivalent transparent material is secured in an appropriate hole of each header 295_X, 295_Y, these caps being centrally located in said headers. Their longitudinal bores 297_X, 297_Y lie coincident with the axes of the cylinder bores 293_X, 293_Y and are closed off at their outer ends by end walls of said caps. The inner ends of said bores 297_X, 297_Y open into the cylinder bores 293_X, 293_Y. These caps are secured as by bolts 298_X, 298_Y to the respective headers 295_X, 295_Y. Fluid passageways 299_{XL}, 299_{XR}, and 299_{YL}, 299_{YR}, are provided in the walls of cylinder blocks 292_X, 292_Y at opposite ends of the respective cylinder bores 293_X, 293_Y.

Slidable cylindrical balancer weights 300_X, 300_Y, preferably of stainless steel are positioned within the respective cylinder bores 293_X, 293_Y. These weights are provided with spaced annular grooves 301_X, 301_Y in their cylindrical surfaces to facilitate free longitudinal sliding motion of the weights 300_X, 300_Y, which are shorter in length than the lengths of the bores 293_X, 293_Y within the latter, while providing an oil film seal between the bore chamber portions on opposite sides of the respective weights 300_X, 300_Y. Axially disposed sight rods 302_X, 302_Y project from ends of the weights 300_X, 300_Y into the respective transparent viewing caps 296_X, 296_Y, wherein their positions may be observed to determine the positions of the respective balance weights 300_X, 300_Y in their cylinder bores 293_X, 293_Y for calibration purposes.

Manifolds 304_X, 304_Y, preferably of brass are secured as by bolts (not shown) to the respective cylinder blocks 292_X, 292_Y so as to overlie the respective fluid passageways 299_{XL}, 299_{XR}, and 299_{YL}, 299_{YR} of these blocks. These manifolds have respective fluid passageways 305_{XL}, 305_{XR}, 305_{YL}, 305_{YR}, whose outlets overlie and communicate with the respective fluid passageways 299_{XL}, 299_{XR}, 299_{YL} and 299_{YR}. Capillary tubes 306_{XL}, 306_{XR}, 306_{YL} and 306_{YR} preferably of soft copper having, for example, .008" I.D. have one of their ends respectively connected to the inlets of respective fluid passages 305_{XL}, 305_{XR}, 305_{YL}, 305_{YR} of the two manifolds 304_X, 304_Y.

The other ends of capillary tubes 306_{XL} and 306_{XR} (FIG. 6) are connected to the outlets of respective passageways 307_{XL}, 307_{XR} in a manifold 308_X, preferably of brass, which latter is secured to the face D of erector body block 174 as by bolts (not shown) so that the inlets of said passageways 307_{XL}, 307_{XR} respectively overlie and communicate with the outlets of respective balancer passageways 179_L and 179_R in said erector body block 174. Similarly, the other ends of capillary tubes 306_{YL} and 306_{YR} are connected to the outlets of respective passageways 307_{YL}, 307_{YR} in a manifold 308_Y, preferably of brass, which latter is secured to the face B of erector body block 174 as by bolts (not shown) so that the inlets

of said passageways 307_{YL} and 307_{YR} respectively overlie and communicate with the respective balancer passageways 183_L and 183_R in said erector body block 174.

In this way, balancer fluid may flow to and from the appropriate power piston chambers 177 and 181 in the erector body block 174 via capillary tubes 306_{XL}, 306_{XR}, 306_{YL}, 306_{YR} to the appropriate sides of balancer cylinder bores 293_X, 293_Y to cause longitudinal shifts of respective balance weights 300_X, 300_Y as may be required in operation as will be presently described.

All the components of the erector system, unless otherwise specified herein are preferably of lightweight non-corrosive material, such as aluminum alloy to reduce the weight of the assembly to a minimum and to provide long wear characteristics as well as ruggedness to the structure.

Electrical system

The electrical system for spinning the gyro rotor 155 and for driving the operating motor 113 of the gear pump 114 is shown diagrammatically in FIGURE 27.

A terminal block 314 having separately insulated terminals 315, 316, 317, 318, 319 and 320 is provided. A common A.C. power source E at 400 c.p.s. and 115 v. is connected via switch 310 and lead wire 322 to terminal 315, via lead wire 321 to common terminal 316 and via switch 311 and lead wire 323 to terminal 317.

A single pole, multiple throw switch 324 has its movable blade 325 connected to terminal 320 by a lead wire 326 while its two contacts 327 and 328 are respectively connected by lead wires 329 and 330 to the terminals 318 and 319.

The terminals 315 and 316 are connected by lead wires 331 and 332 to the primary coil 333 of the gyro power supplying step down transformer T_G. The secondary coil 334 of this transformer providing 45 v. at 400 c.p.s. is connected by lead wire 335 to one end q of the stator field coil or winding 161 and by lead wire 336 to the center tap r of stator field coil 161. A condenser 337 is connected by leads 338 and 339 across the ends t and q of the stator winding 161. With these connections, the rotor wheel 155 is driven in clockwise direction. In the practical embodiment of the invention, the condenser 337 is secured to the bottom portion of the rotor housing 159 (FIG. 4). The connections of the lead wires 335 and 336 to the required parts mounted on the movable gimbal rotor frame Gh is effected through the agency of contact springs 132, 132_a, 147, 147_a, associated contact pins and slip rings all in well known manner so that required electrical connections may be effected without interfering in any way with rotor rotation or free movement of the outer gimbal 135 or the inner gimbal or rotor frame Gh, or of the rotor wheel 155. Any suitable arrangement for effecting this may be utilized.

The electric power for driving the erection pump motor is also derived from the common source E. To this end, the common terminal 316 is connected by lead wire 340 to one end of the primary coil 341 of a step-down transformer T_M. The other end of this primary is connected by lead wire 342 to the terminal 317. Thus, the primary coil 341 is energized at 115 v. at 400 c.p.s. from source E. The secondary coil 343 is in this embodiment designed to produce 32 v. at 400 c.p.s. between its two outermost ends and 17.5 v. at 400 c.p.s. at an intermediate tap point 344. One of the outer terminals of coil 343 is connected by lead wire 345 to terminal 318. The 17.5 v. tap point 344 is connected by lead wire 346 to the terminal 319. The other outer end of secondary coil 343 is connected by lead wire 347 to the center junction V of the stator coil 348 or the erection pump motor 113. The ends W and Z of these stator coils are connected by leads 350, 351 to opposite plates of a condenser 352, and lead 350 as well as the end Z of stator coil 348 are connected by lead wire 356 to the terminal 320. The switch blade 325 thus may be operated to supply the stator field coils 348, either with 32 v. at 400 c.p.s. when switch

blade 325 is in contact with switch contact 327, or with 17.5 v. at 400 c.p.s. when blade 325 is moved into contact with contact 328, thus providing two drive speeds for the erection motor 113, fast speed at 32 v. and slower speed at 17.5 v.

Operation of practical embodiment

Assuming that the gyro G_a is initially in true vertical condition both with respect to the X—X and Y—Y gimbal axes and that the sensor weights 280_x and 280_y respectively lie centralized between their respective pairs of limit stops 286_x , 287_x and 286_y , 287_y , in this condition the movable jets 273_x and 273_y lie centered between the respective pairs of power inlet orifices 236_L , 236_R , and 236_{La} and 236_{Ra} of the respective block receivers 232 and 232a. At this time, too, the power pistons 212 and 212a lie centralized in their respective valve sleeves 202 and 202a. Also, at this time, the balancer weights 300_x and 300_y lie substantially in centralized positions within their respective balancer chambers 292_x and 292_y . In other words, all of the movable components are in centralized positions. The gyro rotor wheel 155 is now energized from the power source E and rotates preferably in clockwise direction. The pump motor 113 is now turned on by moving switch blade 325 into circuit-closing condition with switch contact 327 providing high speed operation of the pump motor 113. The fluid pumped from the casing 110 into its delivery conduit 113 passes from the latter via the passageway 120 and its branch passages 120a upwardly through the gyro supports 122, 122a and through the various interconnected passageways hereinabove described reaches the respective chambers 215 and 215a of the two power valve systems. Because of the bleed arrangements between the pistons and the respective ports 206_L , 206_R and 206_{aL} and 206_{aR} , the bleed fluid under pressure appears at all the erection jet orifices 192a, 193a, 194a and 195a. At this time, also, bleed reaction fluid appears at the feedback reaction jet orifices 243_L, 243_R and 249_L, 249_R. The bleed jet fluid streams delivered by these respective outlets strike the respective jet reaction vanes 291_x and 291_y . The needle valves 244_L, 244_R and 250_L, 250_R are now adjusted carefully to insure the centralized positions of the sensor weights 280_x and 280_y between their respective limit stops. The balance weights 300_x and 300_y are initially positioned in assembly proximate to centralized positions in their balance cylinders 292_x and 292_y . Thus, the pressures on opposite sides of these weights in the cylinders provided by the capillary tubes positions them automatically to gyro balance conditions. In this condition, the shaft 158 of the gyro rotor is vertical.

Assume now that a tilt of the plane F—F' (FIG. 5) if the surface of the gyro rotor casing cover 153 occurs about the X—X axis so that F' lies between horizontal and F above horizontal. This tilt causes the sensor weight 281_x to swing counterclockwise from its centralized position shown in FIG. 7 toward its limit stop 286_x . This immediately causes its movable jet orifice 275_x to swing toward alignment with the power inlet 236_L in the block receiver 232. Thus, fluid under pressure passes via passages 200_L and 199_L in the erector body block and port 209_L to the lefthand side of the power piston 212 causing it to shift toward the right. This rightward shift of the power valve piston 202 causes complete closure of the ports 207_L and opening of the ports 207_R . In consequence, fluid from the chamber 215 can flow freely via the ports 207_R to the jet outlet 192a. At the same time, reaction jet fluid can flow in passage 180_R to the reaction jet orifice 243_R. The erector jet flowing from the erection jet orifice 192a acts to provide an erection torque with the main body of fluid 111 in the container tending to restore the tilted gyro axle 158 to vertical. At the same time, the reaction jet flowing from jet orifice 243_R against the vane 291_x tends to act counter to the gravitational tilt of the sensor weight 281_x tending to restore the power jet 275_x to a centralized position at which

time all the parts move again toward their centralized initial conditions when erection is complete.

If the tilt should occur so that F' is above horizontal and F is below horizontal, the shift of the power piston 202 will be in the opposite direction and the erector jet orifice becoming operative will be erector jet 193a rather than erector jet 192a. The same type of erector action occurs with respect to the Y—Y axis with the power piston 202a being the one then in operation and the jet orifices 194a and 195a being those then providing the erector reaction torques with the fluid 111 in the casing 110.

The capillary tubes 306_{XL} , 306_{XR} , 306_{YL} , 306_{YR} , which are connected through the manifolds 304_X and 304_Y to opposite sides of the balancer weight cylinders 292_x and 292_y are sensitive to pressures at various sides of the respective power pistons 202 and 202a and tend to make the balancer weights 300_x and 300_y self positioning to maintain the entire system in balance should any conditions occur tending to create unbalance.

It is seen, therefore, that the practical embodiment of this invention provides accurate and careful erection both on the X—X and Y—Y axes of the gyro under all conditions and utilization is made of reaction torques created by the jet streams of fluid discharged from the erector jet orifices 192a, 193a, 194a and 195a into the main body of the same jet fluid 111 within the casing 110.

Although specific embodiments of the invention have been described and shown, variations in detail within the scope of the appended claims are possible and are contemplated. There is no intention, therefore, of limitation to the exact disclosure hereinabove presented.

I claim:

1. In combination with a gyroscope, an erector system therefor, said system including jet stream outlets arranged about mutually perpendicular axes, means for directing jet fluid to said outlets, valve means for controlling the discharge of jet fluid from selected of said outlets, pendulum means for operating said valve means, negative feedback means for opposing movement of said pendulum means, container means enclosing the gyroscope and erector system, jet fluid in said container and pumping means within said container for pumping the jet fluid therein to said directing means.

2. In an erector system for gyroscopes, container means enclosing the gyroscope and erector system, jet fluid in said container, jet stream outlets arranged about mutually perpendicular axes, means for directing jet fluid to said outlets, valve means for controlling the discharge of jet fluid from selected of said outlets, gravitationally controlled means for controlling said valve means, negative feedback means for opposing movement of said gravitationally controlled means, and pumping means within said container for pumping the jet fluid therein to said directing means.

3. In an erector system for gyroscopes, container means enclosing the gyroscope and erector system, jet fluid in said container, jet stream outlets arranged about mutually perpendicular axes, conduit means for directing jet fluid to said outlets, valve means for controlling the discharge of jet fluid from selected of said outlets, gravitationally controlled means for controlling said valve means, negative feedback means for opposing movement of said gravitationally controlled means, balancing weight means on said gyroscope, means for altering relative positions of said balancing weight means by integrating portions of a continued unbalanced flow of jet fluid delivered to said conduit means, and pumping means within said container for pumping the jet fluid therein to said conduit means.

4. In an erector system for gyroscopes, container means enclosing the gyroscope and erector system, jet fluid in said container, a universally mounted rotor casing for said gyroscope mounted in said container, a cylinder and a piston member on said casing, a pair of jet stream outlets, a pair of ports in said cylinder, one communicating with each said jet stream outlet, said ports adapted to be

differentially opened and closed upon movement of said piston, pumping means for causing continuous jet fluid flow through said cylinder, ports, and outlets, gravitationally responsive means for controlling the position of said piston, and negative feedback means for opposing movement of said gravitationally responsive means.

5. An erector system as defined by claim 4 wherein said cylinder, piston and jet stream outlets are duplicated and said pairs of jet stream outlets are arranged about mutually perpendicular axes to provide erection about two horizontal axes.

6. In an erector system for gyroscopes, container means enclosing the gyroscope and erector system, jet fluid in said container, a universally mounted rotor casing for said gyroscope mounted in said container, a cylinder and a piston member on said casing, a pair of jet stream outlets, a first pair of ports in said cylinder, one communicating with each said jet stream outlet, said ports adapted to be differentially opened and closed upon movement of said piston, a second pair of ports in said cylinder, gravitationally responsive means for directing a stream of jet fluid differentially through selected of said second ports whereby said fluid will cause said piston to be moved, negative feedback means for opposing movement of said gravitationally responsive means and pumping means for causing continuous jet fluid flow through said erector system.

7. An erector system as defined by claim 6 wherein said cylinder, piston, and jet stream outlets are duplicated and said pairs of jet stream outlets are arranged about mutually perpendicular axes to provide erection about two horizontal axes.

8. In an erector system for gyroscopes, container means enclosing the gyroscope and erector system, jet fluid in said container, a universally mounted rotor casing for said gyroscope mounted in said container, a cylinder and a piston member on said casing, a pair of jet stream outlets, a first pair of ports in said cylinder, one communicating with each said jet stream outlet, said ports adapted to be differentially opened and closed upon movement of said piston, a second pair of ports in said cylinder, gravitationally responsive means for directing a stream of jet fluid differentially through selected of said second ports whereby said fluid will cause said piston to be moved, pumping means for causing continuous jet fluid flow through said erector system, and negative feedback means for opposing movement of said gravitationally responsive means.

9. In an erector system for gyroscopes, container means enclosing the gyroscope and erector system, jet fluid in said container, a universally mounted rotor casing for said gyroscope mounted in said container, a cylinder and a piston member on said casing, a pair of jet stream outlets, a first pair of ports in said cylinder, one communicating with each said jet stream outlet, said ports adapted to be differentially opened and closed upon movement of said piston, a second pair of ports in said cylinder, gravitationally responsive sensor means for directing a stream of jet fluid differentially through selected of said second ports whereby said fluid will cause said piston to be moved, pumping means for causing continuous jet fluid flow through said erector system, a third pair of ports in said cylinder adapted to be differentially opened and closed upon movement of said piston, and a pair of negative feedback jet stream outlets adapted to oppose movement of said gravitationally responsive means by directing a stream of jet fluid thereon in the opposite direction from its gravitationally induced movement, said third ports communicating with said negative feedback jet stream outlets.

10. An erector system as defined by claim 9 wherein said cylinder, piston and jet stream outlets are duplicated and said pairs of jet stream outlets are arranged about mutually perpendicular axes to provide erection about two horizontal axes.

11. In an erector system for gyroscopes, container means enclosing the gyroscope and erector system, jet fluid in said container, a universally mounted rotor casing for said gyroscope mounted in said container, a cylinder and a piston member on said casing, a pair of jet stream outlets, jet fluid conduits connected to said outlets, a first pair of ports in said cylinder, one communicating with each said jet stream outlet, said ports adapted to be differentially opened and closed upon movement of said piston, a second pair of ports in said cylinder, gravitationally responsive sensor means for directing a stream of jet fluid differentially through selected of said second ports whereby said fluid will cause said piston to be moved, pumping means for causing continuous jet fluid flow through said erector system, a third pair of ports in said cylinder adapted to be differentially opened and closed upon movement of said piston, negative feedback conduits connected to said first-named conduits a pair of negative feedback jet stream outlets for said negative feedback conduits adapted to oppose movement of said gravitationally responsive means by directing a stream of jet fluid thereon in the opposite direction from its gravitationally induced movement, said third ports communicating with said negative feedback jet stream outlets, balancing weight means on said gyroscope, and means for altering relative positions of said balancing weight means by integrating portions of a continuous unbalanced flow of jet fluid delivered to said negative feedback conduits.

12. An erector system as defined by claim 11 wherein said cylinder, piston, and jet stream outlets are duplicated and said pairs of jet stream outlets are arranged about mutually perpendicular axes to provide erection about two horizontal axes.

13. In an erector system for gyroscopes, container means enclosing the gyroscope and erector system, jet fluid in said container, a universally mounted rotor casing for said gyroscope mounted in said container, a cylinder and a piston member on said casing, a pair of jet stream outlets, a first pair of ports in said cylinder, one communicating with each said jet stream outlet, said ports adapted to be differentially opened and closed upon movement of said piston, a second pair of ports in said cylinder, gravitationally responsive means for directing a stream of jet fluid differentially through selected of said second ports whereby said fluid will cause said piston to be moved, and pumping means for causing continuous jet fluid flow through said erector system, a third pair of ports in said cylinder adapted to be differentially opened and closed upon movement of said piston and a pair of negative feedback jet stream outlets adapted to oppose movement of said gravitationally responsive means by directing a stream of jet fluid thereon in the opposite direction from its gravitationally induced movement, said third ports communicating with said negative feedback jet stream outlets, balancing weight means on said gyroscope, an enclosure for said balancing weight means fixed to said gyroscope wherein said weight is slidable, integrating means including ports in said enclosure for conducting jet fluid from said cylinder to said enclosure whereby the position of said weight in said enclosure is altered when a continued unbalanced flow of jet fluid occurs in said integrating means.

14. An erector system as defined by claim 13 for providing erection action about two horizontal and mutually perpendicular axes wherein said cylinder, piston, jet stream outlets and balancing weight means are duplicated and said pairs of jet stream outlets are arranged about mutually perpendicular axes to provide erection about both said horizontal axes.

15. In an erector system for gyroscopes, container means enclosing the gyroscope and erector system, jet fluid in said container, a universally mounted rotor casing for said gyroscope mounted in said container, a cylinder and a piston member on said casing, a pair of jet stream outlets, a first pair of ports in said cylinder, one communicating with each said jet stream outlet, said ports

adapted to be differentially opened and closed upon movement of said piston, a second pair of ports in said cylinder, gravitationally responsive means for directing a stream of jet fluid differentially through selected of said second ports whereby said fluid will cause said piston to be moved, negative feedback means for opposing movement of said gravitationally responsive means and pumping means for causing continuous jet fluid flow through said erector system and filter means associated with said pumping means.

16. In an erector system for gyroscopes, container means enclosing the gyroscope and erector system, jet fluid in said container, jet stream outlets arranged about mutually perpendicular axes, means for directing jet fluid to said outlets, valve means for controlling the discharge of jet fluid from selected of said outlets, gravitationally controlled means for controlling said valve means, balancing weight means on said gyroscope, means for

altering relative positions of said balancing weight means by integrating portions of an unbalanced flow of jet fluid delivered to said jet stream outlets, and pumping means within said container for pumping the jet fluid 5 therein to said directing means.
